MOVIE CAMERA

Kazuo Masuyama, Hyogo-ken, Japan, assignor to Fuji
Shashin Film Kabushiki Kaisha, Ashigarakami-gun,
Kanagawa-ken, Japan, a corporation of Japan

Filed Jan. 23, 1969, Ser. No. 15,461

Claims priority, application Japan Aug. 1, 1968

Term of patent 14 years

Int. Cl. D16—02

U.S. Cl. D61—1

FIG. 1 is a perspective view of a movie camera showing my new design;

FIG. 2 is a right side view thereof;

FIG. 3 is a bottom view thereof;

FIG. 4 is a rear view thereof;

FIG. 5 is a front perspective view thereof as seen from the right of FIG. 1, but showing the handle folded at right angles to the camera body;

FIG. 6 is a rear perspective view of the movie camera with the handle folded in a closed position;

FIG. 7 is a perspective view of another embodiment of the FIG. 1 movie camera, but with the handle-cover portion having a raised rim enclosing a simulated leather surface as does the camera body;

FIG. 8 is a right side view thereof;

FIG. 9 is a bottom view thereof;

FIG. 10 is a rear view thereof;

FIG. 11 is a perspective view thereof as seen from the left of FIG. 7, but showing the handle folded at right angles to the camera body;

FIG. 12 is a rear perspective view of the movie camera with the handle folded in a closed position;

FIG. 13 is a perspective view of another embodiment of the FIG. 1 movie camera, but having a squared rather than rounded actuating switch;

FIG. 14 is a right side view thereof;

FIG. 15 is a bottom view thereof;

FIG. 16 is a rear view thereof;

FIG. 17 is a perspective view thereof as seen from the left of FIG. 13, but showing the handle folded at right angles to the camera body; and

FIG. 18 is a rear perspective view of the movie camera with the handle folded in a closed position.

I claim:

The ornamental design for a movie camera, as shown and described.
